[57] CLAIM

The ornamental design for a pedestal or similar article, as shown and described.

DESCRIPTION

FIG. 1 is a perspective view of a pedestal or similar article, showing my new design;

FIG. 2 is a top plan view;

FIG. 3 is a bottom plan view;

FIG. 4 is a front elevational view;

FIG. 5 is an elevation view of the pedestal shown rotated clockwise 45 degrees with respect to FIG. 4;

FIG. 6 is a left side elevation view;

FIG. 7 is an elevation view of the pedestal shown rotated clockwise 45 degrees with respect to FIG. 6;

FIG. 8 is a rear elevational view;

FIG. 9 is an elevation view of a pedestal shown rotated 45 degrees with respect to FIG. 8;

FIG. 10 is a right side elevation view; and

FIG. 11 is an elevation view of the pedestal shown rotated clockwise 45 degrees with respect to FIG. 10.
